RADIATOR CRANK BOX

Application filed February 28, 1931. Serial No. 519,141.

This invention relates to radiators and particularly to an improvement in the radiator forming a part of the cooling system of the internal combustion engine of a motor vehicle.

Such radiators are usually, according to conventional practice, mounted in front of the vehicle engine and comprise upper and lower tanks or headers, for distributing and receiving the engine cooling medium, and a plurality of fluid passageways extending between the tanks for conducting the cooling medium in close proximity to cooling air which may circulate about the fluid passageways. Heretofore, the radiator usually has been mounted above the center line of the engine crank where it will not interfere with the engine starting crank when the latter is engaged with the crank shaft. Recently it has become desirable, in order to lower the vehicle bodies and to enable an increase in the size and capacity of radiators, to mount the radiator in such position that the axis of the crank shaft extended will pass through the cooling portion of the radiator. In order to permit of this, it has become necessary to provide an opening through the radiator unit for receiving a starting crank.

In certain radiator constructions, such as those in which the water cooling passageways comprise a plurality of juxtaposed deformed metal ribbons of generally corrugated form, which together form a plurality of tortuous, substantially vertical water passages extending between the tanks, and horizontal air passages extending between the front and rear faces of the radiator, it has been difficult to provide such a crank opening, since means must be provided to afford passage of water through the passages interrupted by the crank opening, and since it is difficult to securely attach or join such means to the deformed metal ribbons, which usually are of very light gauge.

The present invention comprehends a crank box, of structural formation adapting it for ready securement to a radiator cooling unit of the ribbon or other type, which may be secured to a water tank of the radiator together with and as a part of the cooling unit

in the same manner as such cooling units are ordinarily attached to the water tanks, and in such manner that the water tank may contact with the cooling unit in supporting the crank box.

These and other objects and advantages will become apparent from the following description of one typical embodiment of the invention, reference being made to the accompanying drawing, wherein:

Fig. 1 is a front elevational view of a radiator including upper and lower water tanks, a cooling unit, and the crank box;

Fig. 2 is a vertical sectional view through the portion of the radiator having the crank box, in a plane between the front and rear faces of the radiator;

Fig. 3 is a vertical sectional view of the portion of the radiator shown in Fig. 2, being taken along line 3—3 of Fig. 2; and

Fig. 4 is an enlarged perspective view of one plate member which forms a part of the crank box.

As depicted in Fig. 1, the water cooling unit or radiator may comprise an upper reservoir or tank 10 which may be in communication with an upper part of a water jacket of an internal combustion engine and a lower tank or collecting header 11 in communication with a lower part of an engine water jacket, a cooling unit 12 being disposed between, and providing water passages in communication with the tanks. Water, or other cooling medium, absorbing heat from the engine cylinders in the water jacket may flow into the upper tank 10; may flow downwardly through the cooling unit 12, giving up a portion of its heat to air which may be passed about the water passageways of the cooling unit; and may then be collected in the lower tank and be returned to the engine water jacket.

In the particular form of cooling unit illustrated, the water cooling passages are formed by juxtaposed strips or ribbons 13 of generally corrugated form, adjacent ribbons being sealed along the front and rear faces 14 and 15, seen in Fig. 3, of the radiator. Between each pair of adjacent ribbons is provided a tortuous water passage 16, which extends

between and communicates with the upper and lower tanks.

As shown in Fig. 2, other ribbons 17 or the like, of corrugated or other form may be disposed between each pair of ribbons 13 for increasing the cooling surface of the unit 12. The fins 13 and 17 or the fins 13, if the fins 17 are omitted, provide substantially horizontal air cells 18 which extend between the faces 14 and 15 of the unit and which may serve to pass cooling air through the unit upon forward movement of the vehicle or by the action of an air fan or impeller disposed adjacent one face of the radiator or both.

In the radiator shown in Fig. 1, a crank opening has been formed through cooling unit 12 above the bottom tank 11. This has been effected by terminating certain of the ribbons short of the bottom tank and by inserting a crank box in the space thus provided. It will be noted that the ribbons 13 on both sides of the opening provided by the shortened ribbons present an irregular or corrugated surface and that the passages 16 formed by the shortened ribbons do not communicate with any of the other passages 16 formed between the longer ribbons 13. In order to efficiently provide for water circulation through all of the passages to the lower tank, the crank box 19 has been joined to the cooling unit. It comprises a pair of flanged plates 21, one of which is depicted in Fig. 4, and each of which may have an inwardly extending annular flange 22, defining an aperture 23. A tubular member 24 is joined in telescoped relation with the annular flanges for forming with the plates the crank box unit and for providing a crank opening through the radiator in alignment with the engine crank shaft.

As best shown in Fig. 3, the peripheral flange about each plate has upper and lower portions 25 and 26 respectively which present substantially flat surfaces of considerable area for engagement with the ends of the shortened ribbons 13 and flanges 27 which preferably are formed on the lower water tank 11. The side or edge portions 28 of the peripheral flanges are of corrugated or like contour to complement the irregular faces provided by the adjacent longer ribbons 13. The portions 28 provide a large area of contact between the plates and ribbons 13 insuring a sturdy and water tight construction.

In building up radiators having such crank boxes it has been found to be a material aid to form the plate side flanges of contour to interfit with the ribbons, since the crank boxes may be readily positioned, and during the soldering operation, which is the preferred means of joining the radiator parts, there is less tendency for excess solder to enter the box interior than when straight or plane side flanges are used. Such excess

solder may gather about the passages 13 of the shorter ribbons to impede the flow of water therethrough. Another advantage of the interfitting formation of the side flange portions is that only a thin film of solder is required between the flanges of the plates and the ribbons to insure a water tight joint, whereas with plane flanges a larger quantity of solder is required to fill the substantially triangular crevices between the plate and ribbons, such larger portions of solder being more likely to break away when the radiator is in use to cause leakage of the radiator.

It has also been found that, when the outer faces of the plates are disposed in the plane of the radiator faces 14 and 15, a large quantity of solder may adhere to the plate faces which may later break away together with solder between the plates and ribbons. In the illustrated construction it will be seen that the peripheral flange portions 24, 25 and 28 extend outwardly, so that the faces of the plates are disposed inwardly of the radiator faces 14 and 15. In this manner only the outer edges of the flange portions are exposed to solder during the soldering operation, so that a saving of soldering material and a more durable joinder of the parts is effected.

In certain vehicle constructions, the radiator shell which covers the radiator may be provided with an extension having a crank opening, which overlies the crank box to conceal it from view. As it is desirable to keep the radius of such shell extension at a minimum, the plates of the crank box may have cut-away upper corners as shown in Figs. 2 and 4. These cut-away portions present flat surfaces 29 for abutting contact with certain of the shortened ribbons 13. In order to provide a close fit with the cooling unit, the surfaces 29 may be joined to the upper flange surface 24 by diagonal surfaces 31 which abut diagonal faces of the fins 13. The angular surfaces thus presented at the sides and also the angular surfaces presented at the top of the crank box provide a multitude of soldered connections between the ribbons and the crank box in a plurality of different planes, thus preventing rupture of any substantial number of these connections due to shearing action in the event the radiator structure should be subjected to a blow or movement in one plane, and providing a substantially rigid support and locking structure extending into the radiator structure proper on the three sides of the crank box.

In constructing a radiator according to the present invention, it is preferred to assemble the ribbons 13, 13 or 13, 17 in an assembling frame, together with a pre-assembled crank box, including two plates 21 and a connecting tube 24. After assembly the faces of the unit may be soldered, the adjacent fins 13 being sealed along their edges to provide closed passages 16, the plate flange

portions being sealed to the adjacent long ribbons 13, and the plate top flange portions being sealed to the bottom portions of the shortened fins 13, which preferably have flattened abutment surfaces 32.

5 After the cooling unit including the ribbons and crank box has been formed, it may be joined to the upper and lower water tanks by soldering. The lower plate flange portions 25 present a large surface of contact to the bottom tank flanges 27 to effect a substantial and durable connection, causing the plates 21 to reinforce the joint between the cooling ribbons and the lower tank.

10 It will now be appreciated that the invention provides a simple, economical means of forming a crank opening through the cooling portion of a radiator, in which a crank box, having peripherally flanged plates, with the flanges preferably out-turned, serves to reinforce the radiator assembly; the formation of the plates insures a water tight joint of the box with the cooling unit with a minimum of solder or other sealing material, with an attendant lessening of the probability of the sealing material entering into the interior of the box to interfere with the flow of water thereinto from the water cooling passageways; the crank box provides unrestricted passage for water flowing from the tubes, which are interrupted by the crank opening, into the lower tank; the cooling unit, with the crank box as a part thereof may be attached to the upper and lower tanks in the usual manner by which cooling units and tanks are joined.

15 It will further be understood that the described embodiment is merely illustrative of the principles of the invention, which may be applied to other constructions, and it is accordingly intended that the invention be construed to be of scope commensurate with the appended claims.

20 What is claimed is:

25 1. In a radiator of the corrugated ribbon type having water passageways between the ribbons, certain of the ribbons and water passageways terminating short of the other ribbons and passageways thereof to provide a space bounded by the irregular surfaces of certain of the said other ribbons and by the ends of the shortened ribbons, a pair of plates bounding said space along the front and rear faces of the radiator, each of said plates having a peripheral flange extending outwardly to a face of the radiator, the side portions of the peripheral flanges being of contour to interfit the irregular surfaces of the ribbons bounding the space, the upper portions of said peripheral flanges presenting plane surfaces for abutment with the ends of the shortened ribbons, and the lower portions of said peripheral flanges presenting plane surfaces in the plane of the ends of said other ribbons, a tank extending along the

30 ends of said other ribbons and presenting unbroken surfaces for abutment with the ends of said other ribbons and the lower portions of the peripheral flanges of said plates, and a tubular member extending between said plates for defining a crank opening through the radiator and for cooperating with the plates to provide a passageway between the shortened water passageways and the tank.

35 2. In a radiator of the corrugated ribbon type having water passageways between the ribbons, certain of the ribbons and water passageways terminating short of the other ribbons and passageways thereof, a tank extending along the ends of said last-named ribbons and passageways and having plane portions joined to the ends of said last-named ribbons, said passageways communicating with said tank, the irregular sides of the other ribbons lying adjacent the shortened ribbons and the ends of the shortened ribbons and the plane portion of the tank defining a space through the radiator, an apertured plate disposed along each face of the radiator to close said space, and a tubular member in alignment with the apertures of said plates and extending between said plates, each of the latter having a peripheral flange, portions of said flanges presenting plane surfaces for contact with the ends of said shortened ribbons and water passageways, other portions of said flanges presenting irregular surfaces for interfitting contact with the irregular sides of the other ribbons lying adjacent the shortened ribbons, and other portions of said flanges presenting plane surfaces for contact with the plane portions of said tank.

40 3. In a radiator of the type having tortuous water passages formed by juxtaposed elements, the first of the passages extending between opposite sides of the radiator, and the second of the passages terminating short of one side of the radiator, a tank disposed along one of said sides of the radiator and in communication with the first of said passages and having portions contacting the elements defining the first of said passages, said elements of said first and second passages and said tank defining a space through the radiator, said elements adjacent said space defining irregular walls along said space, a crank box disposed in said space, said crank box comprising a pair of plates and a connecting tube defining an opening through the radiator, each of said plates having a continuous flange, portions of the flanges abutting the end portions of the elements defining the second of said passages, other portions of the flanges being irregular for contacting interfittingly with the irregular walls along said space, and said plates being joined to said tank.

45 4. A crank box for radiators comprising a pair of plates each having a peripheral flange extending outwardly to a face of the

radiator, and each of said plates having an annular flange defining an opening therethrough, and a tubular member telescoped to said annular flanges and joining said plates,
5 the upper and lower portions of the peripheral flanges presenting surfaces adapted for continuous contact with portions of a cooling unit of the radiator and a water tank of the radiator, and the side portions of the peripheral flanges presenting irregular surfaces of
10 portions of the cooling unit of the radiator.
